UNITED STATES PATENT OFFICE.

CHARLES B. UPP, OF READING, PENNSYLVANIA, ASSIGNOR TO DANIEL W. SNYDER,
OF READING, PENNSYLVANIA.

DRYING-FORMER FOR STOCKINGS.

1,106,260.

Specification of Letters Patent.

Patented Aug. 4, 1914.

Application filed April 20, 1914. Serial No. 833,183.

To all whom it may concern:

Be it known that I, CHARLES B. UPP, a citizen of the United States, residing at Reading, in the county of Berks and State of Pennsylvania, have invented certain new and useful Improvements in Drying-Formers for Stockings, of which the following is a specification.

My invention relates to interiorly heated drying-formers adapted for stretching and drying textile fabrics such as stockings; and it consists in the three-part construction hereinafter fully described in connection with the accompanying drawing and the 15 novel features of which are specifically pointed out in the claims.

Figure 1 is mainly a side elevation of a complete former embodying my invention; portions of one of the hollow-casing sections 20 and of the interposed partition-plate being broken away so as to show respectively a full-width portion of said partition-plate and an interior view of the opposed hollow-casing section. Fig. 2 is mainly an elevation 25 at right angles to Fig. 1, but showing a portion thereof in longitudinal section on the line 2—2 of Fig. 1. Fig. 3 is an enlarged cross-sectional view on the line 3—3 of Fig. 1.

The hollow former illustrated is adapted 30 to properly shape a stocking stretched thereon, and is heated as usual by steam supplied through an inlet 2 located on one side of a partition plate in the hollow casing, and discharged through an outlet 3 on the opposite side of said plate.

My improved former is made up of three 35 separately formed parts, two of which are similar hollow-casing sections, 5 and 5^a, respectively, forming opposed longitudinal half portions, while the third part is a partition plate 6 which is interposed between said casing sections 5 and 5^a and tightly united 40 with the latter by cross-wise clamping bolts 7, 7, 7 extending through openings provided therefor in said plate. The sections 5, and 5^a, are preferably right and left castings, each convexly shaped exteriorly and concaved 45 interiorly as shown, and having edge

portions 5^b and a base portion 5^c arranged to 50 abut in a vertical plane, and interior bosses 5^d apertured for the clamping bolts 7, 7; while the partition plate 6 is preferably formed from sheet fiber or like material adapted to provide a satisfactory jointing 55 seat for the abutting casing sections. The abutted base portions 5^c of the latter are provided respectively with inlet and outlet apertures 2, 3 communicating with the hollow casing on opposite sides of the partition 60 plate, and the latter is provided with an opening or openings 10 near the upper end of the casing for passage of the heating medium. The employment of the partition plate 6 as described also permits of very 65 readily and accurately sizing the former, by merely allowing the edge portion thereof to extend more or less beyond the contour line of the abutted half sections 5, 5^a, of the casing, as may be required. These sections 70 are cheaply and satisfactorily produced, and when tightly clamped together against the interposed partition joint-piece as set forth, provide a novel and advantageous structure.

What I claim is:—

1. A drying-former made up of opposed hollow-casing sections and an interposed apertured partition-plate joint-piece, and provided with inlet and outlet means on opposite sides of said partition plate. 75 80

2. A drying-former made up of opposed hollow-casing sections and an interposed apertured partition-plate joint-piece, and provided with inlet and outlet means on opposite sides of said partition plate; the 85 edge portion of the latter extending beyond the opposed hollow-casing sections.

3. A drying-former made up of opposed hollow-casing cast-metal sections and an interposed apertured partition-plate joint-piece of fibrous material, and provided with inlet and outlet means on opposite sides of said partition plate. 90

4. A drying-former made up of opposed hollow-casing cast-metal sections and an interposed apertured partition-plate joint-piece of fibrous material, and provided with inlet and outlet means on opposite 95

sides of said partition plate; the edge portion of the latter extending beyond the opposed hollow-casing sections.

5. A drying-former made up of opposed hollow-casing sections formed with solid base portions and inlet and outlet openings respectively, an interposed apertured partition-plate joint-piece, and cross-wise clamp-

ing bolts for said sections extending through said partition plate.

In testimony whereof I affix my signature in presence of two witnesses.

CHARLES B. UPP.
